BRACELET OR THE LIKE

Paul J. Bellavance, Attleboro, Mass.

Application March 19, 1940, Serial No. 324,823

5 Claims. (Cl. 63—5)

This invention relates to resiliently expandible metal bands or bracelets and the like, and has for its general objects to simplify and cheapen the construction and assembly of such articles and facilitate their repair or the substitution of parts thereof, while producing a bracelet of attractive appearance capable of wide variation.

Bracelets and similar articles of this character have usually been of lazy-tongs construction comprising a relatively large number of relatively small crossed links pivoted together at their ends and points of intersection, and having coiled or torsion springs associated with their pivots. Such articles are expensive to produce and assemble, are difficult to repair if broken or damaged, and are not susceptible to any considerable variation in design. As compared to these, the bracelet of the present invention can be produced and assembled for a small fraction of the cost (for a given character and quality of material), can be caused to assume a far greater variety of forms, and can be repaired or parts thereof replaced or interchanged at greatly reduced cost and required skill.

The more particular objects of the invention, together with means whereby the same may be carried into effect, will best be understood from the following description of an illustrative embodiment thereof shown in the accompanying drawing, this, however, having been chosen for purposes of exemplification merely, as it will be obvious to those skilled in the art that said invention, as defined by the claims hereunto appended, may be otherwise embodied without departure from the spirit and scope thereof.

In said drawing:

Fig. 1 is a perspective view of a bracelet embodying the invention.

Fig. 2 is an enlarged fragmentary plan view of several of the bracelet units with one section of each removed, said units being shown in normal position as in Fig. 1.

Fig. 3 is a similar view showing the bracelet expanded.

Fig. 4 is an enlarged perspective view of one of the units, showing the sections thereof separated.

Fig. 5 is a further enlarged section taken substantially one the line 5—5 of Fig. 3, but with the sections assembled.

Referring to Fig. 1, the bracelet comprises a plurality of units 10 which are, as shown, all of a similar, elongated, generally oval form, although it will be obvious that this shape may be widely varied and also that different units may,

if desired, be of different shapes and other characteristics.

Each of the units 10 is of hollow construction and, as shown most clearly in Figs. 4 and 5, comprises two sections 11 and 12. The section 11 comprises an outer wall 13 and a side wall 14 spaced inwardly from the edge of the wall 13, forming a projecting flange 15. Section 12 comprises an outer wall 16 and a side wall 17 shaped to fit over the side wall 14 of the section 11 and engage at its edge the flange 15. The sections are normally held in assembled relationship, as shown in Fig. 5, by the resilient engagement of indentations 18 in the wall 17 with complementary indentations 19 constituting portions of grooves 20 formed in the wall 14. No soldering or brazing need be employed, the sections being held assembled solely by the resilient inter-engagement of the parts.

The several units are formed in their adjacent walls with registering openings 21 and 22, Fig. 2, each of said openings comprising an aperture 23 (Fig. 4) in the wall 14 of the section 11 and a registering notch 24 in the wall 17 of the section 12. Alternate units A have each secured therein intermediate portions of two springs 25 having preferably oppositely curved free ends 26 which extend obliquely and in crossed relationship through the openings 21 and 22 into both adjacent intermediate units B. The springs 25 are preferably composed of resilient wire and are formed with intermediate coiled portions 29 secured to the end portions of the walls 14 by hooked lugs 27 formed by slitting said walls and bending inwardly the intervening material, as clearly shown in Figs. 4 and 5. The springs 25, which are completely housed within the units, constitute the sole connecting means between contiguous units, which are otherwise free from one another, but the form and arrangement of said springs is such as to tend normally to hold said units in abutting relation and the adjacent walls of contiguous units in engagement, as shown in Figs. 1 and 2. To that end, the springs 25 are slightly pre-wound. Said springs, however, are adapted to yield to permit a limited complete separation of the units and consequent expansion of the bracelet as a whole, as shown in Fig. 3. The extremities of the end portions 26 are enlarged, preferably by bending the same into loops 28 of sufficient size to prevent their withdrawal through the openings 22 in the units B, thereby preventing complete separation of the units in use, although said extremities may, if desired, be of less size than the

openings and act, in the nature of hooks, to resist such separation by engagement with the edges of the openings.

In the event of damage to any of the units, breakage of any of the springs, or other contingency requiring repair of the bracelet, the parts can be readily disassembled for this purpose without the exercise of any great skill or the use of special tools. Since the sections 11 and 12 of the several units are held together solely by their resilient interengagement, the sections of any unit can be readily pried apart to expose the springs 25. Thereafter, by the use of a pair of pliers, the looped extremities 28 of any pair of springs may, if necessary, be straightened out sufficiently to permit their withdrawal through the openings 22, thereby permitting the removal of any desired unit. If necessary to replace a spring, it may be disengaged from its hooked lug 27 and removed and another spring substituted. Thereafter the units can be reassembled by reinserting the ends of the springs through the opening, the looped extremities 28 restored to their original condition, if necessary, and the sections 11 and 12 of the unit in question reassembled and snapped into position, the interengagement of the indentations 18 and 19 being facilitated by the grooves 20. This ease of disassembly of the several units also makes it possible to substitute for any unit a unit of different material or design should it be desired to do so.

I claim:

1. A resiliently expandible bracelet or the like comprising a plurality of hollow units having abutting walls formed with registering openings and springs secured within certain of said units and having free end portions extending obliquely through said openings into contiguous units, said springs normally holding the adjacent walls of contiguous units in engagement but yielding to permit limited separation thereof.

5. A resiliently expandible bracelet or the like, comprising a plurality of normally contiguous units of which at least alternate ones are hollow, and pre-wound coil springs retained in said alternate hollow units, the free ends of each spring being anchored to both adjacent contiguous units.

10 3. A resiliently expandible bracelet or the like, comprising a plurality of normally contiguous hollow units having aligned openings in their adjacent walls, and pre-wound coil springs housed in alternate hollow units, the free ends of each spring extending through said openings into both adjacent contiguous units and being anchored therein.

15 20 25 4. A resiliently expandible bracelet or the like, comprising a plurality of normally contiguous hollow units having aligned openings in their adjacent walls, and a pair of pre-wound coil springs located in each alternate unit, the free ends of each pair of springs crossing each other and normally obliquely extending through said openings into both adjacent contiguous units, and said openings cooperating to deflect said spring ends to further wind the springs on expansion of the bracelet.

25 30 35 5. A resiliently expandible bracelet or the like, comprising a plurality of normally contiguous hollow units having aligned apertures in their adjacent walls, and a pair of pre-wound coil springs located in each alternate unit, the free ends of each pair of springs crossing each other and extending obliquely through said apertures into both adjacent contiguous units and the extremities of said free ends being deformed to engage the apertured walls of said adjacent units in any relative position of the units, and said apertures cooperating to deflect said spring ends to further wind the springs on expansion of the bracelet.

PAUL J. BELLAVANCE.
